UNITED STATES PATENT OFFICE.

WILLARD E. CLOUD, OF CONCORD, NEW HAMPSHIRE, ASSIGNOR, BY DIRECT AND MESNE ASSIGNMENTS, OF TWO-THIRDS TO PHILIP PETHICK, OF SAME PLACE, AND CHARLES D. AUSTIN, OF BROOKLINE, MASS.

CUTTING APPARATUS FOR MOWERS.

SPECIFICATION forming part of Letters Patent No. 360,374, dated March 29, 1887.

Application filed January 5, 1884. Serial No. 116,510. (No model.)

To all whom it may concern:

Be it known that I, WILLARD E. CLOUD, a citizen of the United States, residing at Concord, in the county of Merrimac and State of New Hampshire, have invented certain new and useful Improvements in the Cutting Apparatus for Mowers; and I hereby declare the following to be a full, clear, and exact description thereof.

10 My invention relates to mowing and analogous machines, and has for its object to construct a cutting apparatus for machines of the kind mentioned, in which at no time will all the knives be idle nor at work, but different knives will be at work at different times.

15 I accomplish the object mentioned by the construction, combination, and relationship of parts hereinafter described, so that others skilled in the art may be able to make and use 20 the same, reference being had to the accompanying drawings, and to the letters of reference marked thereon, forming a part of this specification, the invention being particularly pointed out and distinctly claimed at the end 25 of the description of its construction and operation.

Of the drawings, Figure 1 is a plan view of 30 the cutting apparatus, showing the relative position of the knives and guard-fingers when the former are at one extreme limit of their reciprocal movement. Fig. 2 is also a plan view of the same, in which the knives are shown to have traveled to a point which is equal to half their entire stroke. Fig. 3 is a 35 like view showing the knives in the extreme limit of their reciprocal movement opposite to that in which they are represented in Fig. 1.

Similar letters of reference indicate similar parts in all of the figures.

40 A represents the guard or finger bar, and B the guard-fingers. C is the cutter-bar, and D represents the knives, which are riveted in the usual manner to said cutter-bar. E is a section or portion of a pitman-rod, and E' the 45 inner shoe.

In the drawings the machine is represented as provided with fourteen guard-fingers, B, and fifteen knives D, and in Fig. 1 the first knife (1) is hidden in the inner shoe, E', located

equally distant from the first guard-finger (1) 50 as are the guard-fingers from each other, while the fifteenth knife (15) is exactly within the center of the thirteenth guard-finger (13), which brings the eighth knife (8) midway between the sixth and seventh guard-fingers, 55 (6 and 7.)

In Fig. 2 the pitman-rod E has made half of its stroke, by which it will be seen that the eighth knife has reached the center of the seventh guard-finger, while the first knife has 60 moved from the position shown, Fig. 1, halfway to the first guard-finger, and the fifteenth knife has reached a position midway between the thirteenth and fourteenth guard-fingers.

In Fig. 3 the pitman-rod E is represented 65 as having completed its stroke and brought the knives to the extreme limit of their movement opposite that in which they are represented in Fig. 1, so that the tip or point of that knife 1 will be brought substantially in 70 line with the tip of its corresponding guard-finger 1, and the center knife, 8, substantially midway between the two guard-fingers 7 and 8, nearest the center of the series of guard-fingers, while the tip or point of the fifteenth 75 knife will have reached a position substantially in line with the tip of the fourteenth guard-finger. Consequently in the operation of the machine all of the knives are not cutting at the same time, nor are all idle, as in mowing-machines of common construction; but different knives will be at a work at different times.

It will be seen that by my improvements a continuously-cutting apparatus is provided in 85 which the power or force required to operate the knives is even at all times, for at no time will all the knives be idle nor all at work, and the same number of knives will be at work at all times.

Having thus described my invention, what I claim is—

In a cutting apparatus for mowing-machines, the combination, with the finger-bar provided with a plurality of guard-fingers arranged equidistant from each other, of a cutter-bar provided with knives one more in number than the number of fingers on the finger-

bar, and also arranged equidistant from each other, the construction and arrangement of the guard-fingers and knives being such that the distance from point to point of the former 5 will be slightly greater than the distance from point to point of the latter, and that when the point of either end knife shall be exactly in line with the tip of either end guard-finger

the center knife shall be exactly midway between the two guard-fingers nearest the center 10 of said finger-bar, all as and for the purposes hereinbefore set forth.

WILLARD E. CLOUGH.
